UNITED STATES PATENT OFFICE.

ANDREW B. BOUGHAN, OF CHICAGO, ILLINOIS.

HOLDER FOR SCRUB-BRUSHES.

1,132,511.

Specification of Letters Patent. Patented Mar. 16, 1915.

Application filed June 7, 1907. Serial No. 377,760.

To all whom it may concern:

Be it known that I, ANDREW B. BOUGHAN, a citizen of the United States, residing at Chicago, in the county of Cook and State 5 of Illinois, have invented a new and useful Holder for Scrub-Brushes, of which the following is a specification.

The present invention relates to scrub-brushes and has for its object the provision 10 of a scrub-brush holder adapted for use at the end of a handle, and so constructed that an ordinary scrub-brush can be attached and can be renewed at will.

More particularly it is an object of the 15 present invention to provide a holder of considerable weight, so that the scrubbing action may be effected without the need for a downward pressure on the handle, and in the preferred form, the weighting of the 20 scrub-brush is made adjustable to suit the needs or the preference of individual users, and the scrub-brush is readily detachable for renewal.

In the accompanying drawings, Figure 1 25 is a perspective view of a holder complete with its scrub-brush, and Fig. 2 is a vertical section on the line 2—2 of Fig. 1.

In the drawings, the scrub-brush 4 is an 30 ordinary brush with a wooden back and beveled ends of the type long in use for scrubbing floors.

The scrub-brush holder comprises a metal 35 box 9 having its ends 5 shaped to fit the top of the scrub-brush, and is of a length and width to correspond with the dimensions 40 of the brush. This box 9 has a flat metal cover 11 with holes through which wood screws 10 may pass, and each of these screws is received in and supported by an inclosing tube extending from top to bottom of box 45 9, so that the screws not only hold the brush detachably connected to the box, but also

hold cover 11 in place. Within box 9 is a filling 12 of heavy material, such as shot, and the even distribution of this material 45 over the length and width of the brush gives an equalized weighting. To lighten the pressure, cover 11 may be removed and some of the shot taken out, and the structure as a whole can be made lighter or heavier to 50 suit the wish of the operator. Box 9 is provided with an upwardly extending socket 13 positioned intermediate the two beveled ends of the box, whereby a handle 8 may be attached for actuating the brush. 55

I claim:

A brush holder comprising a thin metal box shaped to fit the top of a scrub brush, said box having a flat metal cover and having at one side intermediate the two ends an upwardly extending socket for receiving a wooden handle and rigidly connecting said handle with said box whereby the scrub brush may be actuated, said box inclosing small removable weights and being provided 60 with long screws passed through the cover and through the bottom of the box for attachment to the scrub brush, and a scrub brush corresponding in shape with said box and having a wooden back wherein said 65 screws are received, said screws thereby holding the cover in place and preventing loss of the weights and at the same time holding the scrub brush in place with respect to the holder while permitting ready 70 removal and replacement of the brush when desired, substantially as described. 75

In testimony whereof I have signed my name to this specification in the presence of two subscribing witnesses.

ANDREW B. BOUGHAN.
